(57) **CLAIM**

The ornamental design for a cartridge, as shown and described.

DESCRIPTION

The nature of this product is a cartridge comprising a cardboard cartridge box containing three (3) replenisher containers in a row for replenishing processing solution to an automatic processor. The cartridge is flipped upside down and inserted into an automatic processor, allowing one-step exchange of the cartridge. The cartridge supplies the solution, is used, and removed as is.

FIG. 1 is a perspective view of the cartridge;

FIG. 2 is a front view of the cartridge, the rear view being a mirror image;

FIG. 3 is a left side view of the cartridge;

FIG. 4 is a right side view of the cartridge;

FIG. 5 is a top view of the cartridge; and,

FIG. 6 is a bottom view of the cartridge.

The outline of the article is illustrated with dashed lines, and the solid line portions indicate the portions of the article to which the present design is applied.

The broken lines are for illustration only and form no part of the claimed design.
